UNITED STATES PATENT OFFICE.

HARRY BENTZ, OF MONTCLAIR, NEW JERSEY.

DESIGN FOR AN AIR-HUMIDIFYING WATER-RECEPACLE.

43,749.

Specification for Design.

Patented Apr. 1, 1913.

Application filed September 16, 1912. Serial No. 720,698. Term of patent 14 years.

To all whom it may concern:

Be it known that I, HARRY BENTZ, a citizen of the United States, residing at Montclair, in the county of Essex and State of New Jersey, have invented a new, original, and ornamental Design for an Air-Humidifying Water-Receptacle, of which the following is a specification, reference being had to the accompanying drawings, forming a part thereof, and in which—

Figure 1 is a side elevation, Fig. 2 a top

view, and Fig. 3 an end view of an air-humidifying water receptacle embodying my design.

I claim:

The ornamental design for an air-humidifying water receptacle, as shown.

HARRY BENTZ.
